Des. 193,667
Patented Sept. 25, 1962

193,667

FISH LURE

James A. Ellis, P.O. Box 1527-9, Hawthorne, Nev.

Filed Sept. 14, 1961, Ser. No. 66,718

Term of patent 14 years

(Cl. D31—4)

FIG. 1

FIG. 2

FIG. 3

FIGURE 1 is a perspective view of a fish lure showing my new design.

FIGURE 2 is a side elevational view thereof.

FIGURE 3 is a bottom plan view thereof.

The side not shown is plain.

I claim:

The ornamental design for a fish lure, as shown and described.
